RECLINING ARTICLE OF FURNITURE

Anton Lorenz, Buffalo, N. Y.

Application September 7, 1944, Serial No. 552,987

12 Claims. (Cl. 155—106)

1

My invention relates to articles of furniture, and more particularly to a reclining article of furniture, wherein the seat and a downward extension of the back-rest form movable links and a portion of a support forms the stationary link of a polygonal compound linkage.

An object of my invention is to provide a reclining article of furniture of above described type, wherein the movable members of the article of furniture are very well balanced, so that an occupant resting in the article of furniture may bring the movable members of the article of furniture from one position into another position without great effort.

A further object of my invention is to provide a reclining article of furniture of above described type with a leg-rest, which is pivoted to the seat and controlled by a controlling mechanism in such a manner that the leg-rest may be swung through a relatively large angle during a movement of the members of the article of furniture from their sitting position into their extreme reclined position, so that the leg-rest may be brought into a substantially horizontal position when the members of the article of furniture are in their extreme reclined position.

Another object of my invention is to provide a reclining article of furniture of above described type with or without a leg-rest pivoted to the seat and controlled by a controlling mechanism, wherein the members of the article of furniture may be adjusted by the user of the article of furniture in such a manner, that various changes in the angles between the members of the article of furniture may be obtained during movements of said members of the article of furniture from the sitting position into a certain reclined position.

Still another object of my invention is to improve upon the reclining articles of furniture as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable reclining arm-chair according to the invention, wherein the guiding link is pivoted to the lower connecting link of the polygonal linkage, one side frame of the chair being removed so as to show the mechanism of the arm-chair.

Fig. 2 is a side elevational view of a different

2

embodiment of an adjustable reclining arm-chair according to my invention, wherein the guiding link is pivoted to the front connecting link of the polygonal linkage, one side frame of the chair being removed for the exposure of the mechanical parts of the chair.

Fig. 3 is a side elevational view of still another embodiment of an adjustable reclining arm-chair according to the invention with a leg-rest pivoted to the front portion of the seat and controlled by a controlling link pivoted to the lower connecting link, one side frame of the chair being removed.

Fig. 4 is a side elevational view of an adjustable reclining arm-chair substantially similar to that shown in Fig. 3, wherein, however, the controlling link of the leg-rest is pivoted to an extension of the back-rest.

Fig. 5 is a side elevational view of an arm-chair according to the invention, a portion of a side wall of the chair being broken away,

Fig. 6 is a sectional view taken on line 6—6 of Fig. 5 illustrating the locking device of the chair shown in Fig. 5.

Fig. 7 is a side elevational view of another embodiment of an arm-chair according to the invention, a portion of a side wall of the chair being broken away, and

Fig. 8 is a side elevational view of a further embodiment of an arm-chair according to the invention.

Referring now to Fig. 1, 10 generally indicates the support of an arm-chair, which may be of any conventional type. Said support 10 comprises two side frames 11 connected by a base frame 13, and the side frames provide the arm-rests of the arm-chair.

12 generally indicates a back-rest, 14 indicates a seat, the rear end of which is pivoted to said back-rest 12 at 16. A pair of connecting links 18 and 20 is arranged on each side of the chair. Said pair of connecting links includes a lower connecting link 18 and a front connecting link 20 pivotally connected with each other at 22. The rear end of each lower connecting link 18 is pivoted below the seat 14 at 23 to a downward extension 24 of the back-rest 12. The upper end of each front connecting link 20 is pivoted to the front portion of the seat 14 at 26. The pivotally interconnected extension 24 of the back-rest 12, seat 14, and pair of connecting links 18 and 20 form a four-sided link-system, which is swingably mounted on lugs 28 of the side frames 11 of the support 10 at the pivot point 16 between the back-rest 12 and the seat 14. A guiding link 30 is ar-

ranged on each side of the chair for controlling the movements of the movable members or links 12, 14, 18, 20. One end of each guiding link 30 is pivoted to a rod 33 forming a portion of the side frame 11 at 32 at a point spaced from the pivotal connection 16 between the four-sided link-system 24, 14, 20, 18 and the support 10. The other end of each guiding link 30 is pivoted to the lower connecting link 18 at a point 34 spaced from the pivotal connection 22 between the two connecting links 18 and 20.

As will be readily understood, the various members of the link-system of the chair may be readily made of such a length relative to each other, that the movable members of the chair are very well balanced and may be easily brought from one position into another. Fig. 1 shows in full lines the movable members of the chair in a sitting position. When the occupant of the chair leans his body against the back-rest 12, he may move the movable members of the chair without great effort from the sitting position into a reclined position as shown in dash and dot lines in Fig. 1.

According to Fig. 1 the sitting position of the movable members of the chair is limited by a plate or stop 36 secured to the base frame 13 of the support 10 for cooperation with the extension 24 of the back-rest 12. The extreme reclined position is limited by a stop 38 arranged on the support 10 for cooperation with the back-rest 12 proper.

Furthermore, according to Fig. 1, the chair is provided with a locking device generally indicated by 40. Said locking device 40 comprises a rod 42 pivoted to the seat 14 at 44 and engaged by a clamping sleeve 46; said clamping sleeve may be tightened on the rod 42 by tightening an adjusting knob 50 on the threaded end of a bolt 48 projecting from the side wall of the chair for locking the movable members 12, 14, 18, 20 of the chair in a desired comfortable position. The locking device is of the same general organization as the locking device 440 shown in Figs. 5 and 6 and described hereinafter in connection with said Figs. 5 and 6.

In the embodiment shown in Fig. 1, the foot-rest 52 is mounted on the rear portion of the base frame 13 of the support 10. Such an arrangement of a foot-rest 52 is advisable, if chairs according to the invention are arranged in rows, for example, in an airplane, railroad car, or theater. If desired, the occupant of a chair may place his feet on the foot-rest 52 mounted on the rear portion of the chair in front of him.

In the embodiment shown in Fig. 2, 110 generally indicates the support of a chair. Said support comprises two side frames 111 connected with each other by a wall 115. The rear end of the seat 114 is pivoted to the back-rest 112 at 116. The showing of Fig. 2 is somewhat diagrammatical, the cushions on the back-rest and the seat are omitted. It is self-evident that such cushions may be arranged on the back-rest and the seat, if desired. The back-rest 112 has the extension 124 projecting downwardly from the pivot point 116 between the back-rest 112 and seat 114. Again, the pivotally interconnected extension 124 of the back-rest 112, the seat 114, and the pair of connecting links 118, 120 form a four-sided link-system swingably mounted on the support 110 at 116 for movement about an axis coinciding with the axis of the pivotal connection between the back-rest and the seat. According to Fig. 2, however, one end of the guiding link 130 is pivoted to

an intermediate point of the front connecting link 120 at the point 154 spaced from the pivotal connection 122 between the two connecting links 118, 120, while the other end of said guiding link is pivoted to the support at 132 at a point spaced from the pivotal connection 116 between the four-sided link-system and the support. Thus, the chair comprises a first four-sided link-system having three movable links 114, 120, 130 and one stationary link formed by the portion of the support 110 between the pivots 116 and 132 and a second four-sided link-system having four movable links 114, 120, 118, 124. The links 114 and 120 are common to both link-systems, so that said link-systems being superimposed represent in combination a polygonal compound linkage. The extreme sitting position of the movable members of the chair is limited by a stop 136 arranged on the support 110 for cooperation with the extension 124 of the back-rest and the extreme reclined position of the movable members is limited by a stop 138 arranged on the support 110 for cooperation with the back-rest 112. Furthermore, the chair is provided with a locking device 140 for locking the movable members of the chair in any desired position. The operation of the chair shown in Fig. 2 corresponds to the operation of the chair shown in Fig. 1. The extreme sitting position is shown in full lines, the extreme reclined position is shown in dash and dot lines.

In the embodiment of a chair shown in Fig. 3, 210 indicates the support of the chair comprising two side frames 211 connected with each other by cross bars 215, 236, 238. The rear end of the seat 214 is pivoted to the back-rest 212 at 216. Similar to the embodiment shown in Fig. 1 the pivotally interconnected extension 224 of the back-rest 212, the seat 214, and the pair of connecting links 218, 220 form a four-sided link-system swingably mounted on the support 210 at 216 for movement about an axis coinciding with the axis of the pivotal connection between the back-rest and the seat. Furthermore, similar to the embodiment shown in Fig. 1, one end of the guiding link generally indicated by 230 is pivoted to the lower connecting link 218 at a point 234 spaced from the pivotal connection 222 between the two connecting links 218, 220. However, contrary to the embodiment shown in Fig. 1, the other end of the guiding link 230 is pivoted to the support 210 at the point 256 below the seat. Furthermore, contrary to the showing of Fig. 1, the lower connecting link 218 is bent and has an upwardly extending arm. In spite of these differences in the construction and arrangement of some members of the chair, the principle of operation of the chair according to Fig. 3 is the same as that of the chair shown in Fig. 1. The sitting position of the movable members of the chair limited by the cross-bar or stop 236 is shown in full lines, while the extreme reclined position limited by the cross-bar or stop 238 is shown in dash and dot lines. The locking device 240 may be used to lock the movable members of the chair in any desired position be it the sitting position or the extreme reclined position or any intermediate position.

The chair shown in Fig. 3 shows the additional feature of a leg-rest 258 pivoted to the front end 70 of the seat 214 at 260. The movements of said leg-rest 258 are controlled by a controlling link generally indicated by 262. One end of said controlling link 262 is pivoted to the lower connecting link 218 at the point 222, which coincides with 75 the pivot between the lower connecting link 218

and the front connecting link 220. The other end of said controlling link 262 is pivoted to the leg-rest 258 at 264. As will be readily understood, the leg-rest 258 is swung about its pivot 260 by means of the controlling link 262 driven by the lower connecting link 218, when the movable members of the chair are brought from one position into another one.

The chair shown in Fig. 3 has furthermore some additional useful features by the arrangement of means for varying and adjusting the relative position between certain of the pivotal connections of the movable members of the chair. According to Fig. 3, the seat 214, the lower connecting link 218, the leg-rest 258, and the support 210 are provided with series of holes 266. As will be readily understood, the pins 222, 226, 234, 256, 260, 264 may be inserted by the user of the chair into selected holes of said series of holes 266. Depending on the selection of the holes, the distance between two or more pivotal connections of the movable members may be changed with the result of different relative positions between the movable members of the chair in various reclined positions. For example, if the user of the chair prefers a less inclined position of the seat in the extreme reclined position than that shown in dash and dot lines in Fig. 3, he may obtain this feature by changing the position of one or more of above mentioned pins. Furthermore, for a still greater variety of the adjustments, the guiding link 230 consists of two telescopic elements 268, 270, which may be held in any adjusted position by a set screw 272. Likewise, the length of the controlling link 262 may be varied by a change in the relative position between the telescopic members 274, 276 forming said controlling link and being held in an adjusted position by a set screw 278. For example, if the length of the telescopic controlling link 262 is adjusted in the manner shown in Fig. 3, the user of the chair may bring the leg-rest 258 and the seat 214 in alignment with each other, when the movable members of the chair are held in the sitting position or a reclined position, by extending the length of the telescopic controlling link 262. Furthermore, for example if in the sitting position of the movable members of the chair the length of the telescopic controlling link is adjusted in such a manner that in said sitting position the leg-rest is in alignment with the seat, an alignment of the leg-rest with the seat in a reclined position may be obtained by shortening the length of said telescopic controlling link to a certain extent before the movable members of the chair are brought from the sitting position into the reclined position.

In the chair shown in Fig. 4, 310 indicates the support of the chair comprising two side frames, 311 connected with each other by cross-bars 315, 336, 338. The rear end of the seat 314 is pivoted to the back-rest 312 at 316. The rear end of the lower connecting link 318 is pivoted to the extension 324 of the back-rest at 323, and the upper end of the front connecting link 320 is pivoted to the front end of the seat at 326. Said pivotal connection 326 connects also the leg-rest 358 with the seat. One end of the guiding link 330 is pivoted to the lower connecting link 318 at a point 334 spaced from the pivotal connection 322 between the two connecting links 318, 320, while the other end of said guiding link 330 is pivoted to the support 310 at 332. The four-sided link-system formed by the extension 324 of the back-rest, the pair of connecting links 318,

320, and the seat 314 is swingably mounted on the support 310 at 316. The movements of the members of the polygonal linkage are controlled by the guiding link 330, and the movements of the leg-rest 358 are controlled by a controlling link generally indicated by 362. One end of said controlling link is pivoted to the extension 324 at 380, the other end of said controlling link is pivoted to the leg-rest 358 at 364. The sitting position limited by the cross-bar or stop 338 is shown in full lines. When the user of the chair leans his body against the back-rest 312, he may move the movable members of the chair from said sitting position into a reclined position, for example into the extreme reclined position limited by the cross-bar or stop 338 and shown in dash and dot lines. The locking device 340 may be used for holding the movable members of the chair in any desired comfortable position.

In the embodiment shown in Fig. 4, the controlling link 362 is of telescopic construction so that the relative position between the leg-rest and the seat may be adjusted by a shortening or lengthening of the length of the controlling link 362.

Fig. 5 illustrates an arm-chair according to the invention, wherein 410 indicates the support comprising two side frames 409 and 411 connected with each other by cross-bars 415, 436, 438. The rear end of a seat 414 is pivoted to a back-rest 412 at 416. A pair of connecting links 418 and 420 is arranged on each side of the chair. Said pair of connecting links includes a lower connecting link 418 and a front connecting link 420 pivotally connected with each other at 422. The rear end of each lower connecting link 418 is pivoted below the seat 414 at 423 to a downward extension 424 of the back-rest 412. The upper end of each front connecting link 420 is pivoted to the front portion of the seat 414 at 426. The thus pivotally interconnected extension 424 of the back-rest 412, the seat 414 and the pair of connecting links 418, 420 form a four-sided link-system, swingably mounted on the support 410 at 416 coaxial with the pivotal connection between the back-rest 412 and the seat 414. One end of a telescopic guiding link 430 is pivoted to an intermediate point of the front connecting link 420 at a point 454 spaced from the pivotal connection 422 between the two connecting links 418, 420, while the other end of said guiding link 430 is pivoted to the support 410 at 432 at a point spaced from the pivotal connection 416 between the four-sided link-system and the support. Thus, the chair comprises a first four-sided link-system having three movable links 414, 420, 430, and one stationary link formed by the portion of the support 410 between the pivots 416 and 432, and a second four-sided link-system having four movable links 414, 420, 418, 424. The links 414 and 420 are common to both link-systems, so that said link-systems being superimposed represent in combination a polygonal compound linkage.

A leg-rest 458 is swingably mounted on the front end of the seat 414 at 460. The movements of said leg-rest 458 are controlled by a telescopic controlling link 462. One end of said controlling link 462 is pivotally connected with the pivotal connection 422 between the connecting links 418 and 420. The other end of said controlling link 462 is pivoted to the leg-rest 458 at 464.

When the occupant resting on the chair leans his body against the back-rest 412, he may move

the movable members of the chair without great effort from the sitting position shown in full lines into a reclined position shown in dash and dot lines.

The sitting position of the movable members of the chair is limited by the cross-bar or stop 436, against which the downward extension 424 of the back-rest 412 may abut. The extreme reclined position is limited by the cross-bar or stop 438, against which the back-rest 412 proper may abut.

The movable members of the chair may be held in any desired position by means of a locking device generally indicated by 440. According to Figs. 5 and 6, said locking device comprises a rod 442 pivoted to the seat 414 at 444. A bolt 448 having a head 499 and a threaded end 497 is inserted into apertures 495 and 493 of a clamping sleeve 446 engaged with said rod 442. The portion 491 of the bolt 448 has a square cross-section fitting into the square aperture 493 whereby the bolt 448 is prevented from rotation. A tubular member 489 inserted into a hole 487 of the side frame 409 of the support 410 is arranged between the clamping sleeve 446 and a locking knob 450 screwed on the threaded end 497 of the bolt 448. When said locking knob 450 is loosened, the rod 442 may freely slide in the clamping sleeve 446, so that the movable members of the chair may be readily moved from one position into another one. If the locking knob 450 is tightened, the tubular member 489 and the head 499 of the bolt 448 press against the clamping sleeve 446, whereby the latter is tightly pressed against the rod 442, so that the movable members of the chair are held in the adjusted position.

The arm-chair shown in Fig. 5 is furthermore provided with means for varying and adjusting the relative position between certain of the pivotal connections of the movable members of the chair. According to Fig. 5, the seat 414, the front connecting link 420, the leg-rest 458 and the support 410 are provided with series of holes 466. As will be readily understood, the pins 426, 432, 454, 464 may be inserted by the user of the chair into selected holes of said series of holes 466. Depending on the selection of the holes, the distance between two or more pivotal connections of the movable members may be changed with the result of different relative positions between the movable members of the chair in various reclined positions. For example, if the user of the chair prefers a less inclined position of the seat in the extreme reclined position than that shown in dash and dot lines in Fig. 5, he may obtain this feature by changing the position of one or more of above mentioned pins. Furthermore, for a still greater variety of the adjustments, the guiding link 430 consists of two telescopic elements 468, 470, which may be held in any adjusted position by a set screw 472. Likewise, the length of the controlling link 462 may be varied by a change in the relative position between the telescopic members 474, 476 forming said controlling link and being held in an adjusted position by a set screw 478. For example, if the length of the telescopic controlling link 462 is adjusted in the manner shown in Fig. 5, the user of the chair may bring the leg-rest 458 and the seat 414 in alignment with each other when the movable members of the chair are held in the sitting position or a reclined position by extending the length of the telescopic controlling link 462. Furthermore, for

example, if in the sitting position of the movable members of the chair the length of the telescopic controlling link is adjusted in such a manner that in said sitting position the leg-rest is in alignment with the seat, an alignment of the leg-rest with the seat in a reclined position may be obtained by shortening the length of said telescopic controlling link to a certain extent before the movable members of the chair are brought from the sitting position into the reclined position.

According to the embodiment of a reclining chair shown in Fig. 7, the four-sided link-system 514, 520, 518, 524 is swingably mounted on the support 510 at an intermediate point 585 of the back-rest 512 rigidly connected with the link 524. Said swingable connection 585 is spaced from the pivotal connection 516 between the back-rest 512 and the seat 514. The upper end of the guiding link 530 is pivoted to the support 510 at 532 and the lower end of said guiding link 530 is pivoted to an intermediate point of the front connecting link 520 at 554. The effective length of the lower connecting link 518 between the pivots 522 and 523 equals the effective length of the front connecting link 520 between the pivots 522 and 526.

The sitting position of the movable members of the chair is limited by the cross-bar 536 of the support 510 cooperating with the downward extension 524 of the back-rest 512. The extreme reclined position of the movable members of the chair is limited by the cross-bar 538 of the support 510 cooperating with the back-rest 512.

According to the embodiment of a reclining chair shown in Fig. 8, the four-sided link-system 614, 620, 618, 624 is swingably mounted on the support 610 at an intermediate point 683 of the seat 614 spaced from the pivotal connection 616 between the back-rest 612 and the seat 614. The upper end of the guiding link 630 is pivoted to the support 610 at 632 and the lower end of said guiding link 630 is pivoted to an intermediate point 654 of the front connecting link 620. The effective length of the lower connecting link 618 between the pivots 622 and 623 is larger than the effective length of the front connecting link 620 between the pivots 622 and 626.

The sitting position of the movable members of the chair is limited by the cross-bar 636 of the support 610 cooperating with the downward extension 624 of the back-rest 612. The extreme reclined position of the movable members of the chair is limited by the cross-bar 638 cooperating with the back-rest 612.

I have described preferred embodiments of my invention, but, of course, numerous changes and omissions may be made without departing from the spirit of my invention.

For example, the lower connecting link and the front connecting link may be of different lengths, as shown in the drawings, or of the same lengths.

For example, only one pair of connecting links and only one guiding link arranged in the center of the chair may be used instead two pairs of connecting links and two guiding links as described in connection with the drawings.

Moreover, means of the type shown in Fig. 3 or of a different type for varying and adjusting the relative position between the pivotal connection of movable members of the chair may be arranged in any embodiment of an article of furniture, according to the invention.

My invention may be applied to many types of chairs, for example arm chairs, reclining chairs for the household, garden chairs, chairs for use in railroad cars, chairs for use in airplanes, desk chairs, etc. Furthermore my invention may be applied to other articles of furniture such as sofas, for example.

What I claim is:

1. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, and a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting link forming a four-sided link-system of a polygonal linkage, and said four-sided link-system being swingably mounted on said support at a point spaced from the pivotal connection between the support and the guiding link and spaced from the pivotal connection between the front connecting link and the guiding link.

2. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, and a guiding link, the upper end of said guiding link being pivoted to said support, the lower end of said guiding link being pivoted to said front connecting link at a point spaced from the pivotal connection between said two connecting links, said pivotally interconnected extension of the back-rest, seat and pair of connecting links forming a four-sided link-system of a polygonal linkage, and said four-sided link-system being swingably mounted on said support at a point spaced from the pivotal connection between the support and the guiding link and spaced from the pivotal connection between the front connecting link and the guiding link.

3. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, and a

guiding link, one end of said guiding link being pivoted to said support, the other end of said guiding link being pivoted to an intermediate point of said front connecting link, said pivotally interconnected extension of the back-rest, seat and pair of connecting links forming a four-sided link-system of a polygonal linkage, and said four-sided link-system being swingably mounted on said support at a point spaced from the pivotal connection between the support and the guiding link and spaced from the pivotal connection between the front connecting link and the guiding link.

4. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, and said four-sided link-system being swingably mounted on said support at a point spaced from the pivotal connection between the support and the guiding link and spaced from the pivotal connection between the front connecting link and the guiding link, and means whereby the position of the pivotal connection between two movable links of the polygonal linkage may be adjusted.

5. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, and said four-sided link-system being swingably mounted on said support at a point spaced from the pivotal connection between the support and the guiding link and spaced from the pivotal connection between the front connecting link and the guiding link, and means whereby the position of the pivotal connection between two movable links of the polygonal linkage may be adjusted, said guiding link being of variable length, and means whereby the length of said guiding link may be adjusted.

6. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, said four-sided link-system being swingably mounted on said support at a point spaced from the pivotal connection between the support and the guiding link and spaced from the pivotal connection between the front connecting link and the guiding link, a leg-rest swingably mounted on the front portion of said seat, and a controlling mechanism operatively connected with a link of the polygonal linkage and said leg-rest for controlling the movements of the latter.

7. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, said four-sided link-system being swingably mounted on said support at a point spaced from the pivotal connection between the support and the guiding link and spaced from the pivotal connection between the front connecting link and the guiding link, a leg-rest swingably mounted on the front portion of said seat, a controlling mechanism operatively connected with a link of the polygonal linkage and said leg-rest for controlling the movements of the latter, means whereby the position of the pivotal connection between two movable links of the polygonal linkage may be adjusted, said guiding link being of variable length, and means whereby the length of said guiding link may be adjusted.

8. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally

connected with each other, the rear end of said lower connecting link being pivoted to said extension of the back-rest below the seat, the upper end of said front connecting link being pivoted to the front portion of said seat, a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, said four-sided link-system being swingably mounted on said support at a point spaced from the pivotal connection between the support and the guiding link and spaced from the pivotal connection between the front connecting link and the guiding link, a leg-rest swingably mounted on the front portion of said seat, and a controlling link, one end of said controlling link being pivoted to said lower connecting link, the other end of said controlling link being pivoted to said leg-rest.

9. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, said four-sided link-system being swingably mounted on said support at a point spaced from the pivotal connection between the support and the guiding link and spaced from the pivotal connection between the front connecting link and the guiding link, a leg-rest swingably mounted on the front portion of said seat, a controlling link, one end of said controlling link being pivoted to said lower connecting link, the other end of said controlling link being pivoted to said leg-rest, said controlling link being of variable length, and means whereby the length of said controlling link may be adjusted."

10. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, and a guiding link, one end of said guiding link being pivoted to said support, the other end of said guiding link being pivoted to said front connecting link at a point spaced from the pivotal connection between said two connecting links, said pivotally inter-

connected extension of the back-rest, seat and pair of connecting links forming a four-sided link-system of a polygonal linkage, said four-sided link-system being swingably mounted on said support at a point spaced from the pivotal connection between the support and the guiding link, and said swingable connection of the link-system with the support being coaxial with the pivotal connection between the back-rest and the seat.

11. A reclining article of furniture, comprising: a support of connected side frames, a back-rest, a seat pivotally connected with said back-rest, said back-rest having an extension projecting downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, and a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, said four-sided link-system being swingably mounted on said support at a point spaced from the pivotal connection between the support and the guiding link, and said swingable connection of the link-system with the support being arranged at a point of the seat spaced from the pivotal connection between the back-rest and the seat.

12. A reclining article of furniture, comprising: a support of connected side frames, a back-rest, a seat pivotally connected with said back-rest, said back-rest having an extension projecting

downwardly beyond the pivotal connection between the back-rest and the seat, at least one pair of connecting links including a lower connecting link and a front connecting link pivotally connected with each other, the rear end of said lower connecting link being pivoted to said extension of the back-rest below the seat, the upper end of said front connecting link being pivoted to the front portion of said seat, and a guiding link, one end of said guiding link being pivoted to said support, the other end of said guiding link being pivoted to said front connecting link at a point spaced from the pivotal connection between said two connecting links, said pivotally interconnected extension of the back-rest, seat and pair of connecting links forming a four-sided link-system of a polygonal linkage, said four-sided link-system being swingably mounted on said support at a point spaced from the pivotal connection between the support and the guiding link, and said swingable connection of the link-system with the support being arranged at a point of the seat spaced from the pivotal connection between the back-rest and the seat.
